SANDAL ROLLER SKATE

Joseph P. Famolare, Jr., Florence, Italy, assignor to
Famolare, Inc., New York, N.Y.

Filed Mar. 1, 1974, Ser. No. 447,314

Term of patent 14 years

Int. Cl. D21—02

U.S. Cl. D34—14 C

FIG. 1

FIG. 2

FIG. 3

FIG. 4

FIG. 5

FIG. 6

FIG. 1 is a left side elevational view of a sandal roller skate showing my new design;

FIG. 2 is a top plan view thereof;

FIG. 3 is a right side elevational view thereof;

FIG. 4 is a bottom plan view thereof;

FIG. 5 is a rear elevational view thereof; and

FIG. 6 is a front elevational view thereof.

I claim:

The ornamental design for a sandal roller skate, substantially as shown and described.
